CLAIM

The ornamental design for a cabinet for a water cooler, as shown and described.

DESCRIPTION

FIG. 1 is a perspective view of a cabinet for a water cooler showing my new design.

FIG. 2 is a front elevational view thereof.

FIG. 3 is a right side elevational view thereof.

FIG. 4 is a rear elevational view thereof.

FIG. 5 is a left side elevational view thereof.

FIG. 6 is a top plan view thereof; and,

FIG. 7 is a perspective view thereof, showing the lid removed and the doors in the open position.

The surfaces or portions of the article not shown in the drawing or described in the specification form no part of the claimed design.
